CLAIM

The ornamental design for a nostril dilator, as shown and described.

DESCRIPTION

FIG. 1 is a front, top, right side perspective view of a nostril dilator, showing our new design;

FIG. 2 is a rear elevational view thereof;

FIG. 3 is a bottom plan view thereof;

FIG. 4 is a left side elevational view thereof; and,

FIG. 5 is a perspective view of a second embodiment of the nostril dilator with the only difference residing in the knobs on the tips of the nostril dilator and all other portions being substantially the same as that shown in FIGS. 1-4.

FIG. 1

FIG. 5

FIG. 2

FIG. 4

FIG. 3
